UNITED STATES PATENT OFFICE.

HENRY W. BORNTRAEGER, OF PITTSBURG, PENNSYLVANIA, ASSIGNOR TO
CARNEGIE BROTHERS & CO., (LIMITED,) OF SAME PLACE.

PILE OF IRON.

SPECIFICATION forming part of Letters Patent No. 268,385, dated December 5, 1882.

Application filed May 3, 1882. (No model.)

To all whom it may concern:

Be it known that I, HENRY W. BORNTRAEGER, of Pittsburg, in the county of Allegheny and State of Pennsylvania, have invented a new and useful Improvement in Piles of Iron; and I do hereby declare the following to be a full, clear, and exact description thereof.

Heretofore in working up railroad-rails into merchantable shapes they have been cut, both longitudinally and laterally, into pieces, and then piled preparatory to being placed in the heating-furnace. Usually these piles have been bound around by straps or bands of iron. By my invention I make use of the rails without slitting or binding. I make a pile exactly adapted to the production of an I or channel beam by interlocking the heads and flanges of the rails used therein with each other. At the same time I so dispose the metal that the reduction of the pile in rolling, necessary to compacting it and closing up the interstices in the formation of the web of the I or channel beam, shall not break down, distort, or weaken the fiber. Thus I retain the full strength of the material.

To enable others skilled in the art to make and use my invention, I will now describe it by reference to the accompanying drawings, in which—

Figure 1 is a perspective view of my improved pile, and Figs. 2 to 7 are, respectively, cross-sections of the beam as it appears after six passes through the rolls.

Like letters of reference indicate like parts in each.

In forming this pile I use six rails, *a b c d e f*, and top and bottom pieces, *g h*. The pieces *g h* are flat bars of a suitable width, thickness, and length. Two rails, *a* and *b*, are placed side by side on the bottom piece, *h*. Then the two rails *c* and *d* are placed on their sides on top of the rails *a b*, the web of *c* resting on the head of *a*, and the web of *d* resting on the head of *b*, and with their heads or flanges inward and abutting against each other. I prefer to put the flanges of the rails *c* and *d* inward, as shown in the drawings. I then place the two remaining rails *e f* on top, in an inverted position, their heads resting upon the upper sides of the webs of the rails *c* and *d*, and then I

place the top piece, *g*, upon the bottoms of the rails *e f*. I then insert muck or other bars, *i k*, in the interstices of the pile, between rails *a b* and *e f*. The pile thus formed is locked together by the arrangement of the rails, and is lifted and placed in the heating-furnace in the position shown in Fig. 1. The heat of the furnace softens the metal and causes the constituents of the pile to weld or stick together sufficiently to enable it to be handled or taken from the furnace and inserted into the rolls without falling to pieces. The rolls have preferably six passes, which reduce the pile successively to the forms in cross-section. (Shown by Figs. 2 to 7.) The first pass closes up the interstices of the pile, and in doing so forces the rails *c* and *d* into the web part of the beam and welds the constituents of the pile firmly together. The result is the I-beam shown by Fig. 7, in which the fiber of the metal remains unstrained, whereby I obtain an I-beam of great strength and rigidity.

The advantages of my improved pile consist in its simplicity of arrangement, the avoidance of the use of bands or ties, the ease and safety with which it may be handled, the rapidity and thoroughness with which it may be heated, owing to its open structure, and the consequent saving of time and fuel in the heating-furnace, the small cost of preparing it, and the utilization of railroad-rails without slitting or re-forming them.

The top and bottom and filling pieces should be of the same material as that of the rails composing the pile.

The fillers *i k* may be omitted, if desired.

A simpler pile, which may be used for making a similar shape, may consist of the rails *a c e*, with top and bottom pieces of suitable width.

What I claim as my invention, and desire to secure by Letters Patent, is—

1. A pile composed of one or more sets of three rails each, two of the rails of each set arranged with their heads to the center and abutting against the opposite sides of the web of an interposed rail, substantially as and for the purpose specified.

2. A pile for making I-beams, consisting of two rails placed in their normal position, two

rails resting with their webs on the heads of the first two, two rails in an inverted position, and resting by their heads on the webs of second two, and top and bottom pieces, substantially as and for the purposes described.

3. A pile for making I-beams, consisting of six rails arranged as described, and top and bottom and filling pieces, substantially as and for the purposes described.

In testimony whereof I have hereunto set my hand this 28th day of April, A. D. 1882.

HENRY W. BORNTRAEGER.
